UNITED STATES PATENT OFFICE.

CHARLES J. THATCHER, OF NEW YORK, N. Y.

ELECTROLYTIC CELL.

1,388,216.

Specification of Letters Patent. Patented Aug. 23, 1921.

Application filed October 21, 1919. Serial No. 332,228.

To all whom it may concern:

Be it known that I, CHARLES J. THATCHER, a citizen of the United States, and a resident of 27 West 95th St., in the city and county of 5 New York and State of New York, have invented certain new and useful Improvements in Electrolytic Cells, of which the following is a specification.

The invention relates to a cell suitable for 10 conducting electrolytic operations on a commercial scale; and it has for its object a cell of this character which may be readily assembled, of substantial construction, and such as to reduce the introduction of foreign 15 material to a minimum, but at the same time constructed in manner to be conveniently taken apart for cleaning of the cell; also, to provide a construction which will afford a view of the interior of the cell during operation and permit removal of samples. A 20 further object of the invention consists in means for stirring the electrolyte so as to induce a proper and positive circulation thereof.

25 The nature of the invention will be best understood when described in connection with the accompanying drawings, in which—

Figure 1 is an elevation of the improved electrolytic cell.

30 Fig. 2 is a plan thereof.

Fig. 3 is a vertical section taken on the line 3—3, Fig. 2.

Fig. 4 is a transverse section taken on the line 4—4, Fig. 3.

35 Fig. 5 is a plan of the cell with a number of the parts removed.

Fig. 6 is a fragmentary vertical section taken on the line 6—6, Fig. 2.

40 Fig. 7 is a perspective detail view of a member employed to close the cell.

Similar characters of reference designate corresponding parts throughout the several views.

Referring to the drawings, 10 designates 45 a suitable and outer container such as a jar of stone ware, porcelain or like material, on the bottom of which is supported, through three feet or blocks disposed 120° apart to prevent rocking, an inner or separator vessel 11.

This vessel is constructed of diaphragm 50 material of a semi-permeable nature, permitting the free diffusion of ions therethrough, but serving to prevent, for all practical purposes, any transmission of fluid 55 through the walls of said vessel. A very satisfactory material for this purpose is that

disclosed in my Patent No. 1,291,253 of January 14th, 1919, as well as in my co-pending application, Serial No. 266535, filed by me the 13th day of December, 1918, and 60 consisting of granular material as "filtros" impregnated with a gelatinous material as sodium silicate. The vessel 11 may extend slightly above the top of vessel 10, and within the same is contained an electrode 12 composed of plates which extend from the bottom of the vessel 11 and are shown as projecting somewhat beyond the upper end thereof. This latter vessel may be of lead 65 or other suitable material such as graphite plates suitably held together as by means of lead coated angle pieces 13 and bolts 14, and is secured relatively to the vessel 11 in that its lower edges 15 fit into corresponding 70 grooves 16 provided in the bottom of the vessel 11. Suitable dowels or blocks 17, moreover, are provided near the top of the electrode to further locate the same with reference to the vessel 11.

The vessel 11 affords either the cathode 75 or anode compartment, as may be desirable, into which, as hereinbefore described, extends the electrode 12, while the space between the vessel 11 and the outer vessel 10 constitutes either the anode or cathode compartment, and into which dip suitable electrodes 18, such as lead plates, which are supported from the rim of the vessel 10 as by being hung over a square frame piece 19 of 80 suitable conducting material, which rests upon the top of the vessel 10, and to which frame electrical connection may be made in any convenient manner.

The opening at the top between vessel 11 and electrode 12 may be closed, for example, 85 by means of removable glass plates 20 and 21; and, furthermore, the top of the vessel formed by the electrodes 12 is arranged to be closed by means of two plates 22 of glass, over which rests a further closure member 23 of lead, having downwardly extending lugs 24 designed to contact with the edges of the plates 22 and secure same in position, the other edges of the plates 22 abutting upwardly extending bars or guide strips 25 secured to the outer end of the electrode vessel 12, and which hold the electrode 12 and thereby the vessel 11 in place.

The closure member 23 may be provided 90 with an opening 26 through which samples of the electrolyte within the vessels 11 and 12 may be obtained, and with a further

opening 27 centrally disposed with reference thereto and through which is arranged to pass a tubular stirring member 30. This member extends through a false bottom 31 of the vessel 12, said false bottom having a suitable opening 32 therein to permit of the location of the stirring member, and being slit, as indicated, to allow a T termination or arms 33 to pass therethrough. A further opening 34 is provided to allow of the insertion of a tube (not shown) for removal of the finished charge. By means of the false bottom 31, a chamber is provided between the bottom of vessel 11 and the said false bottom, and in which arms 33 at the lower end of the stirrer are caused to rotate to thoroughly mix the electrolyte contained in the vessels, as well as to induce a circulation of said electrolyte between the walls of the vessels 11 and 12, the lower portion of the latter for this purpose being provided with suitable perforations 35 and similarly the upper portions with perforations 36. Due to the rapid rotation of the arms 33, the electrolyte is drawn downwardly through the openings 32 and 34 of the false bottom, and forced outwardly through the openings 35 into the space between the two vessels 11 and 12, and returned to the former through the openings 36. Moreover, the stirrer is provided at the upper portion of the vessel 12 with an inlet opening 37 through which electrolyte, especially the lighter portion where the same consists of a mixture of several liquids of different specific gravity, is drawn inwardly and through the tube, to be expelled with considerable velocity from the arms 33 of said tube. With liquids of lighter specific gravity, this arrangement is particularly desirable in affording a thorough mixture at the beginning of a run and where fresh liquid is added during a run. At the same time, the whole body of liquid is worked upwardly between the separator 45 and electrode vessels.

The stirring and circulation mechanism, hereinbefore described, is carried by a suitable and removable superstructure which may consist, as shown, of four uprights 40 secured to the upper portion of the vessel 10 as by means of wires or rods 41 passing therethrough and tightened by screw bolts 42 or other suitable means. At the top, these uprights carry beams 43 adjustably secured thereto as by means of screws 44, and to these said beams are secured, also, the guide bars 25 leading to the vessel 12. A transverse beam 45, consisting of two separated clamping parts suitably held together, is carried by the two beams and extends over the center of the apparatus to afford holding or clamping means for the stirrer member 30. To this end, there is cemented to this member, which is preferably constructed of glass, a metal sleeve 50; and near the top of

said sleeve is secured a collar 51. Abut the sleeve 50 and beneath the collar 51 is a further or bearing sleeve 52 which is held coaxially with the stirrer 30 and vessel 12 by the clamping portions of beam 45, the stirrer being supported vertically through the collar 51 resting upon the sleeve 52 which affords the bearing for its rotation. Rotation may be transmitted thereto in any suitable manner, as for example through a belt 53 and pulley 54, which latter is secured to the outer projecting end of said stirrer member. In this manner, the said stirrer member is so mounted as to be readily removable from the cell, as is also the whole super-structure, tanks, etc.

The mechanical means provided herein in conjunction with the particular construction of cell shown afford a positive upward circulation of liquid in a narrow passage between diaphragm and electrode induced by the centrifugal action of stirrer, the circulating liquid being composed of portions drawn from the upper layers as well as from the body of the electrolyte itself. In this manner, there is insured a constant supply of the raw material, even when such is non-miscible in and of lesser specific gravity than the other constituents of the electrolyte.

It will be understood that the separator vessel may be dispensed with in electrolyses where separation of the anolyte and catholyte liquids is not essential or desirable; and that other forms of stirring devices than that shown may be positioned within the hollow electrode so as to induce rapid upward or downward circulation between the hollow electrode and the separator vessel or adjacent electrode.

I claim:

1. An electrolytic cell, comprising: a suitable container; a separator vessel therein; an electrode in the space between said vessel and container; and a hollow electrode within said vessel, said hollow electrode being provided with a false bottom.
2. An electrolytic cell, comprising: a suitable container; a separator vessel therein; an electrode in the space between said vessel and container; and a hollow electrode within said vessel, said hollow electrode being provided with a false bottom and having perforations near the top and at the bottom portion below said false bottom.
3. An electrolytic cell, comprising: a suitable container; a separator vessel therein; an electrode in the space between said vessel and container; a hollow electrode within said vessel, said hollow electrode being provided with a false bottom and having perforations near the top and at the bottom portion below said false bottom; and means to induce a circulation of electrolyte between said hollow electrode and the said vessel.
4. An electrolytic cell, comprising: a suit-

- able container; a separator vessel therein; an electrode in the space between said vessel and container; and a hollow electrode within said vessel, said hollow electrode being composed of plates suitably secured and positioned relatively to the said vessel, through its lower edges fitting corresponding grooves in the bottom of the said separator vessel.
10. 5. An electrolytic cell, comprising: a suitable container; a separator vessel therein; an electrode in the space between said vessel and container; a hollow electrode within said vessel, said hollow electrode being provided with a false bottom and having perforations near the top and at the bottom portion below said false bottom; a stirring tube passing through said hollow electrode and the false bottom thereof, having an opening near the upper portion of said hollow electrode and outlets at its lower end.
15. 6. An electrolytic cell, comprising: a suitable container; a separator vessel therein; an electrode in the space between said vessel and container; a hollow electrode within said vessel, said hollow electrode being provided with a false bottom and having perforations near the top and at the bottom portion below said false bottom; a stirring tube passing through said hollow electrode and the false bottom thereof, having an opening near the upper portion of said hollow electrode and oppositely-directed, open-ended tubular arms at its lower end below said false bottom.
20. 7. An electrolytic cell, comprising: a suitable container; a separator vessel therein; an electrode in the space between said vessel and container; a hollow electrode within said vessel, said hollow electrode being provided with a false bottom and having perforations near the top and at the bottom portion below said false bottom; a stirring tube passing through said hollow electrode and the false bottom thereof, having an opening near the upper portion of said hollow electrode and outlets at its lower end below said false bottom; and means to rotatably mount said stirrer member on said cell.
25. 8. An electrolytic cell, comprising: a suitable container; a separator vessel therein; a hollow electrode in the space between said vessel and container, said hollow electrode being provided with a false bottom and having perforations near the top and at the bottom portion below said false bottom; means to close the top of the vessel and hollow electrode; a stirring tube passing through said hollow electrode and the false bottom thereof, having an opening near the upper portion of the said hollow electrode and outlets at its lower end below said false bottom; and means to rotatably mount said stirrer member on said cell.
30. 9. An electrolytic cell, comprising; a suit-
- able container; a separator vessel therein; a hollow electrode extending above the top of said vessel and provided with guide strips; glass plates resting upon said top of the vessel and closing the space between same and the hollow electrode; glass plates partly closing the top of said hollow electrode; and a lead strip between said last-named glass plates and having lugs abutting the lateral edges thereof and pressing the opposite edges of said glass plates against the guide strips of the hollow electrode.
35. 10. An electrolytic cell, comprising: a suitable container; a separator vessel therein; a hollow electrode in the space between said vessel and container, said hollow electrode being provided with a false bottom and having perforations near the top and at the bottom portion below said false bottom; a stirring tube passing through said hollow electrode and the false bottom thereof, having an opening near the upper portion of the said hollow electrode and outlets at its lower end below said false bottom; and means to close the top of the vessel and hollow electrode, said means being provided with a central opening to receive a stirrer member.
40. 11. An electrolytic cell, comprising: a suitable container; a separator vessel therein; an electrode in the space between said vessel and container; a hollow electrode within said vessel, said hollow electrode being provided with a false bottom and having perforations near the top and at the bottom portion below said false bottom; a stirring tube passing through said hollow electrode and the false bottom thereof, having an opening near the upper portion of said hollow electrode and outlets at its lower end below said false bottom; and means to close the top of the vessel and hollow electrode and be drawn downwardly into the lowermost compartment of the hollow electrode as well as drawn through the stirrer member and expelled from the lower end thereof.
45. 12. An electrolytic cell, comprising: a suitable container; a separator vessel therein; an electrode in the space between said vessel and container; a hollow electrode within said vessel, said hollow electrode being provided with a false bottom and having perforations near the top and at the bottom portion below said false bottom; a stirring tube passing through said hollow electrode and the false bottom thereof, having an opening near the upper portion of said hollow electrode and outlets at its lower end below said false bottom; and means to close the top of the vessel and hollow electrode, said means being provided with a central opening to receive the stirrer member, and the said stirrer member having a metal sleeve.

1
secured thereto, a collar at the upper portion of said sleeve, a bearing sleeve about said first-named sleeve and below said collar, and means to secure said bearing sleeve 5 to the container.

13. An electrolytic cell, comprising: a suitable container; a separator vessel therein; an electrode in the space between said vessel and container; a hollow electrode within 10 said vessel, said hollow electrode being provided with a false bottom and having perforations near the top and at the bottom portion below said false bottom; a stirrer tube passing through said hollow electrode and 15 the false bottom thereof, having an opening near the upper portion of said hollow electrode and outlets at its lower end below said false bottom; means to close the top of the vessel and hollow electrode, said means being provided with a central opening to receive the stirrer member, the latter having a metal sleeve secured thereto; a collar at the upper portion of said sleeve, a bearing sleeve about said first-named sleeve and below said collar, and means to secure said bearing sleeve to the container, comprising a removable superstructure having a plurality of uprights attached to the container, beams adjustable thereon, and a transverse two-part clamping member adapted to secure the 25 said bearing sleeve of the stirrer, the latter being provided at its outer end with a suitable pulley member.

14. A cell for the production of paramido-35 phenol and its compounds, comprising: a container; a vessel therein composed of granular diaphragm material impregnated with a suitable gelatinous medium, the space between same and the said container forming the anode compartment of the cell and 40 containing sulfuric acid and a lead anode; a cathode member within said vessel and

composed of carbon plates, said vessel and cathode being designed to retain a mixture of nitro benzol and sulfuric acid; and means 45 extending within said cathode to induce a circulation and mixture of the electrolyte.

15. An electrolytic cell, comprising a hollow electrode, an adjacent electrode so positioned as to provide a relatively narrow 50 space between it and the hollow electrode, and a stirring device to induce rapid circulation of the electrolyte between the electrodes and through the hollow electrode.

16. An electrolytic cell, comprising a hollow electrode provided with perforations, an adjacent electrode so positioned as to provide a relatively narrow space between it and the hollow electrode, and a stirring device to induce rapid circulation of the electrolyte 55 between the electrodes.

17. An electrolytic cell, comprising a hollow electrode provided with perforations at the top and bottom, an adjacent electrode so positioned as to provide a relatively narrow 65 space between it and the hollow electrode, and a stirring device to induce rapid circulation of the electrolyte between the electrodes.

18. An electrolytic cell, comprising a hollow electrode, an adjacent member, and 70 means for inducing circulation of electrolyte through the hollow electrode and the space between said member and said hollow electrode.

19. An electrolytic cell, comprising a hollow electrode, an adjacent member, and a stirring device within said hollow electrode to induce circulation of electrolyte through the space between said member and said 75 hollow electrode.

Signed at New York in the county of New York and State of New York this 20th day of October, A. D. 1919.

CHARLES J. THATCHER.
